DESIGN FOR AN ELECTRIC FENCE CONTROLLER CABINET

Clifford Brooks Stevens, Milwaukee, Wis., assignor to Simplicity Manufacturing Company, Port Washington, Wis., a corporation of Wisconsin

Application July 12, 1941, Serial No. 102,106

Term of patent 7 years

To all whom it may concern:

Be it known that I, Clifford Brooks Stevens, a citizen of the United States, residing at Milwaukee, in the county of Milwaukee and State of Wisconsin, have invented a new, original, and ornamental Design for an Electric Fence Controller Cabinet, of which the following is a specification, reference being had to the accompanying drawing, forming part thereof.

Figure 1 is a perspective view showing the front, top and one end of the cabinet; and

Figure 2 is a perspective view showing the front, top and opposite end of the cabinet.

The back and bottom of the cabinet are plain surfaces.

The characteristic features of my design reside in those portions shown in full lines in the drawing.

I claim:

The ornamental design for an electric fence controller cabinet, as shown and described.

CLIFFORD BROOKS STEVENS.
